(57) **CLAIM**

The ornamental design for a toy construction block, as shown and described.

DESCRIPTION

FIG. 1 is a top perspective view of the full-length toy construction block;

1 Claim, 10 Drawing Sheets

FIG. 2 is a top perspective view of the block from the diagonally opposite corner from the view of FIG. 1;

FIG. 3 is a bottom perspective view of the block;

FIG. 4 is a bottom perspective view of the block from the diagonally opposite corner from the view of FIG. 3;

FIG. 5 is a top plan view of the block;

FIG. 6 is a bottom plan view of the block;

FIG. 7 is a front side view of the block;

FIG. 8 is a rear side view of the block;

FIG. 9 is a left side view of the block;

FIG. 10 is a right side view of the block;

FIG. 11 is a top perspective view of a modified embodiment of the design shown in FIGS. 1-10.

FIG. 12 is a top perspective view of the half-length block from the diagonally opposite corner from the view of FIG. 11;

FIG. 13 is a bottom perspective view of the half-length block;

FIG. 14 is a bottom perspective view of the half-length block from the diagonally opposite corner from the view of FIG. 13;

FIG. 15 is a top plan view of the half-length block;

FIG. 16 is a bottom plan view of the half-length block;

FIG. 17 is a front side view of the half-length block;

FIG. 18 is a rear side view of the half-length block;

FIG. 19 is a left side view of the half-length block; and,

FIG. 20 is a right side view of the half-length block.
